UNITED STATES PATENT OFFICE

138,606

DESIGN FOR A CUTTING MACHINE

William A. Phllis, Warren, Ohio, assignor to Beaver Pipe Tools, Inc., Warren, Ohio, a corporation of Ohio

Application June 14, 1944, Serial No. 114,005

Term of patent 14 years

(Cl. D37—1)

To all whom it may concern:

Be it known that I, William A. Phllis, a citizen of the United States, residing at Warren, in the county of Trumbull and State of Ohio, have invented a new, original, and ornamental Design for a Cutting Machine, of which the following is a specification, reference being had to the accompanying drawings, forming a part thereof.

In the drawings, Fig. 1 is a perspective view of a cutting machine embodying my new design, looking from a position adjacent the left front

corner; and Fig. 2 is a perspective view thereof
looking from a position adjacent the left rear corner.

I claim:

The ornamental design for a cutting machine,
substantially as shown.
